METHOD AND APPARATUS FOR CONTROL-
LING THE THICKNESS AND UNIFORMITY
OF A LIQUID COATING ON WIREHarold Beedy, Western Springs, Ill., assignor to
Western Electric Company, Incorporated, New
York, N. Y., a corporation of New York

Application July 19, 1947, Serial No. 762,080

8 Claims. (Cl. 117—93)

1.

This invention relates to methods and apparatus for controlling the thickness and uniformity of a coating on a base and more particularly to methods and apparatus for controlling the thickness and uniformity of enamel on wire.

When wire is coated by continuously feeding the wire through an enamel bath and then through a drying or baking chamber at constant speed, the production of a smooth uniform enamel coating of the desired thickness presents a difficult problem. In passing through the enamel bath the wire picks up excess enamel thus forming droplets and tears along the wire, the amount of excess being dependent upon the viscosity of the enamel, the more viscous the greater excess.

Objects of this invention are to provide new and efficient methods and apparatus for removing excess liquid coating from a wire.

In accordance with one embodiment of this invention, wire is passed through an enamel bath and then passed through a helix along the longitudinal axis of the helix, the helix being at an electrical potential several thousand volts above that of the wire being enameled. As the freshly coated wire passes through the helix the excess enamel is stripped from the wire by electrostatic forces due to the potential difference. From there the wire is passed through baking ovens to cure the enamel.

A complete understanding of the invention will be had by reference to the following detailed description taken in conjunction with the accompanying single figure drawing which is a diagrammatic illustration of one embodiment of the invention herein.

In order to practice the invention, enamel may be applied to a wire 10 by any suitable method, for example, as shown in the drawing the wire 10 may be taken from a supply spool 11 and dipped into an enamel bath 12 by passing the wire 10 around a metal pulley 13 submerged in the enamel bath which may be contained in any suitable tank 14. The wire 10 is pulled through the enamel bath by rotative power applied to a take-up reel 15 to which the end of the wire has been attached after threading it around the pulley 13 and another metal pulley 20, the wire being held under reasonable tension at all times.

In accordance with old practices in the art the wire 10 as it emerged from the enamel bath would pass through a drying oven to cure the enamel without any attempt to remove the excess enamel or to maintain the coating on the wire uniform. Other practices in the art include the

2.

stripping of excess enamel by passing the wire through stripping dies before it enters the drying oven. However, with this invention the matter of stripping excess enamel from the wire and maintaining the coating uniform is simplified by passing the wire through a helical de-tearing electrode 21 which is maintained at a potential difference of several thousand volts from that of the wire 10 by means of a suitable source of high voltage 22 preferably of direct current, the negative side of which is connected to the helix and the positive side connected to the wire 10 through the pulleys 13 and 20 which may also be grounded. The apparatus will operate with the polarity reversed, that is with the positive side connected to the helix. In practice it was found that the corona point is reduced by connecting the negative side of the power supply to the helix. The helix 21 is more efficient if it is formed from a conductor having a cross section quite a bit larger than that of the wire being enameled. A resistor 23 may be connected in series with the power supply to limit the current in case of arcs caused by a flash-over.

As the wire 10 passes through the helical electrode 21 the high potential difference between the helix and the wire 10 will cause the electrostatic forces set up therebetween to pull the excess of the freshly applied enamel from the wire 10, and the stripping effect is made uniform due to the spiral path of the electrostatic forces through which the wire is being drawn. Because of the helical shape of the de-tearing electrode, the electrostatic forces move around the wire as it progresses and do not tend to pull the material which remains on the wire to one side as would be the case if a plane were used as a de-tearing electrode.

The thickness of the enamel coating may be controlled by controlling the voltage on the de-tearing electrode 21. After the wire has passed through the electrified helix it may be passed through a suitable oven 24 to bake and cure the enamel coating.

The dimensions of the helical electrode 21, including its diameter, the pitch of the spiral turns, and the size of the conductor of which it is formed together with the amount of voltage applied between the helix and the wire 10 are dependent upon the viscosity of the enamel bath and the linear speed of the moving wire in order to obtain a desired uniformity and thickness of coating. Such factors may be correlated to obtain the desired result and may be arrived at by experiment. The diameter, pitch and length of the helix would

be determined experimentally for any given application. In general, a material of high viscosity requires a higher voltage to remove the excess material than material of low viscosity and would require a larger diameter helix to avoid electrical breakdown. It might also require a somewhat longer helix to assure complete removal of tears or droplets. The length of the spiral and its pitch will also be largely dependent upon the speed of movement of the wire.

Because of the efficient de-tearing and stripping action of the invention herein, enamels of relatively high viscosity may be used without the necessity of mechanical stripping dies and a smooth coat of enamel may be applied with fewer passes than is possible under older practices by making possible the use of more viscous enamel. The apparatus herein is very simple, it is non-clogging and will pass splices and welds in the wire which could not go through mechanical dies.

What is claimed is:

1. A method of removing excess liquid enamel from a wire being enameled comprising subjecting said wire to a corkscrew-shaped spiral electrostatic field and moving the wire through said field in line with the major axis of said spiral field.

2. In a method of enamelling wire, the step of removing excessive liquid enamel from said wire by passing said wire through an open helical electrostatic field in line with the major axis of said field.

3. A method of controlling the thickness and uniformity of a liquid coating on a wire comprising applying a liquid coating on a wire, and stripping excess coating from the wire by passing the wire through a helically shaped electrostatic field in line with the major axis of said helical field, the adjacent turns of the helix being spaced apart sufficiently to create unbalanced forces on the portion of the wire in said field.

4. A method of controlling the thickness and uniformity of enamel coating on wire comprising applying a liquid coating of enamel to said wire, establishing a field of electrostatic forces spiralling openly along and around said wire, imparting relative movement axially of the wire between the wire and the spiral field of electrostatic force to strip the excess liquid from said wire, and drying the enamel remaining on the wire.

5. An apparatus for stripping the excess of a liquid coating from wire comprising an open

helical electrode, means for drawing said liquid coated wire through said helical electrode along the longitudinal axis thereof, and means connected to said helical electrode and adapted to be connected to said wire for establishing a potential difference between said helical electrode and said wire to strip the excess liquid coating from said wire by electrostatic force.

6. An apparatus for coating wire with enamel comprising means for applying liquid enamel to a wire, means for moving said wire longitudinally, and means for setting up an electrostatic force extending spirally around and along said moving wire to strip the excess enamel from said wire; the last said means comprising an open helical electrode and a source of relatively high voltage connected to said electrode and said wire.

7. An apparatus for controlling the thickness and uniformity of an enamel coating comprising a helical electrode through which a wire having a coating of liquid enamel may be passed coaxially, the adjacent turns of said helix being spaced substantially apart and a source of voltage coupled to said electrode and to said wire, said voltage being of such value as to set up electrostatic forces strong enough to strip the excessive enamel from the wire.

8. A method of controlling the thickness and uniformity of enamel coating on a wire, which comprises applying a coating of liquid enamel on a wire, creating a helically shaped electrostatic field having substantial spaces between adjacent turns of the helix, advancing the wire through the helically shaped electrostatic field in line with the major axis of the helical field to strip the excess enamel from said wire by electrostatic force, and then baking the enamel.
